UNITED STATES PATENT OFFICE.

CLAUDE M. NEWMAN, OF CHICAGO, ILLINOIS.

INVALID'S TABLE.

Application filed July 28, 1925. Serial No. 46,641.

To all whom it may concern:

Be it known that I, CLAUDE M. NEWMAN, a citizen of the United States, residing at Chicago, in the county of Cook and State 5 of Illinois, have invented certain new and useful Improvements in Invalids' Tables, of which the following is a specification.

This invention relates to an invalid's table and one object of the invention is to provide a table which may be attached to the head of a bed at one side thereof and swung from an operative position with the table top disposed across the bed in front of the patient to an inoperative position at one 15 side of the bed and close against the wall with the table top disposed vertically.

Another object of the invention is to so construct the bed-engaging clamp and foldable table top carrying arm that the sections from which the arm is formed may be disposed in edge to edge contact when the device is folded and have the free end of the table top carrying section of the arm supported by the bracket.

Another object of the invention is to provide a table of this character which will be simple in construction and consists of a few parts.

This invention is illustrated in the accompanying drawing, wherein—

Figure 1 is a top plan view showing the table attached to a bed and in an operative position;

Fig. 2 is a view similar to Fig. 1 showing the table folded and swung to one side of the bed against the wall;

Fig. 3 is a view showing the table in front elevation and in an operative position, and

Fig. 4 is an enlarged sectional view 40 through the bed-engaging clamp.

The table is intended for use in hospitals so that meals can be served to patients confined to their beds and has, therefore, been illustrated in connection with a bed 1 which 45 is of the conventional type used in hospitals and includes a head 2 formed of bent metal. The clamp 3 which forms a portion of the table is to be secured at one side of the head 2 of the bed in engagement with the post 4 thereof and has, therefore, been formed with a recess 5 which receives the bed post, as shown in Fig. 4. The jaw 6 of the clamp is pivotally mounted at one end by means of a pin 7 which extends through the hinge ear 8 of the jaw and the jaw is 50 formed with a recess 9 into which the bed 55 post fits when the jaw is closed and secured by a fastener bolt 10. The bolt 10 passes through an ear 11 which extends from the free end of the jaw and is screwed into a 60 threaded socket 12 formed in the body of the clamp. Ears 13 extend outwardly from the body of the clamp in spaced relation one above the other and carry a pivot pin 14 which serves to pivotally mount the inner 65 section 15 of a foldable table carrying arm. The outer section 16 of the table carrying arm is of a thickness corresponding to the inner arm 15 and at its inner end is formed with a head 17 from which extend forks 18. 70 The forks 18 extend above and below the offset side portion of a head 19 formed at the forward end of the inner arm section 15 and are secured by a pivot pin 20 so that the outer section 16 may be swung in a horizontal plane into and out of side to side contact with the inner section. When in the folded position shown in Fig. 2, the free end of the outer arm section 16 fits between the ears 13 of the clamp and, therefore, the outer section 75 of the folding arm will be supported and unnecessary strain removed from the pin 20. The table top 21 is hingedly connected with the outer arm section by hinges 80 22 so that it may be swung vertically from 85 a folded inoperative position to an operative position in which it is disposed horizontally, as shown in Figs. 1 and 3, and rests upon the upper edge face of the outer arm section. It is important that the table 90 top be prevented from accidental moving from the operative position to an inoperative position and, therefore, there has been provided a latch 23 which is in the form of an elongated block pivotally secured to 95 the under face of the table top and adapted to be swung into transverse relation to the table top with one end engaging the side edge face of the outer arm section to which the hinges 22 are fastened. It will be readily 100 understood that, when the latch block is in the position shown in Figs. 1 and 3, the table top will be prevented from swinging to the inoperative position shown in Fig. 2 and there will be no danger of the patient accidentally striking the forward portion of 105 the table top and causing it to be tilted. While it has been stated that the table will be used in connection with a bed, it will be understood that it could also be used in connection with chairs and attached to the back 110 of the chair at one side thereof.

Having thus described the invention, I claim:

1. An invalid's table comprising a bracket adapted to be secured to a support and extend therefrom, said bracket including outwardly extending hinge ears spaced one above the other, an arm formed of inner and outer sections pivotally connected for swinging movement in a horizontal plane from a folded position to an extended position, said inner section having one end pivotally mounted between said hinge ears and the free end portion of said outer section adapted to fit between the hinge ears when in a folded position, and a table top hinged to said outer section for vertical swinging movement from an inoperative position against the outer side face of the outer section to an operative position resting upon the upper edge face thereof.
2. An invalid's table comprising a bracket adapted to be secured to a support and extend therefrom, said bracket including outwardly extending hinge ears spaced one above the other, an arm formed of inner and outer sections pivotally connected for swinging movement in a horizontal plane from a folded position to an extended position, said inner section having one end pivotally mounted between said hinge ears and the free end portion of said outer section adapted to fit between the hinge ears when in a folded position, and a table top carried by said outer section and movable from an inoperative position to an operative position.

3. An invalid's table comprising a bracket adapted to be secured to a support and extend therefrom, an arm formed of inner and outer sections, said inner section being pivotally connected with said bracket for swinging movement in a horizontal plane and said outer section being pivotally connected with the outer end of the inner section for swinging movement in a horizontal plane from an extended position to a folded position with its free end engaged with and supported by said bracket, and a table top carried by said outer section and movable from an inoperative to an operative position.

4. An invalid's table comprising a bracket adapted to be secured to a support and extend therefrom, an arm including inner and outer sections, said inner section being pivotally connected at its inner end to said bracket for swinging in a horizontal plane and having its outer end portion widened transversely to form a head having a side portion projecting beyond one side face of the section, said outer section being pivotally connected at one end to the projecting side portion of the head of said inner section for swinging in a horizontal plane from an extended position to a folded position against the said side edge face of the inner section with its free end supported upon said bracket, and a table top carried by said outer section and movable from an operative to an inoperative position.

In testimony whereof I affix my signature,
CLAUDE M. NEWMAN. [L. S.]
